UNITED STATES PATENT OFFICE.

ORTUS E. MOATS, OF CHICAGO, AND JAMES D. BENBOW, OF AURORA, ILLINOIS,
ASSIGNORS TO WESTERN WHEELED SCRAPER COMPANY, OF AURORA, ILLINOIS,
A CORPORATION OF ILLINOIS.

DUMP-CAR.

1,351,114.

Specification of Letters Patent. Patented Aug. 31, 1920.

Application filed September 26, 1918. Serial No. 255,795.

To all whom it may concern:

Be it known that we, ORTUS E. MOATS, a citizen of the United States, and a resident of Chicago, in the county of Cook and

5 State of Illinois, and JAMES D. BENBOW, a citizen of the United States, and a resident of Aurora, in the county of Kane and State of Illinois, have invented certain new and useful Improvements in Dump - Cars, of
10 which the following is a specification, reference being had to the accompanying drawings.

Our invention relates to dump cars in which the car bed is centrally pivoted on the under body of the car so as to be capable of tilting to discharge its load at either side, and which are provided with power-operated means, such as a compressed air operated plunger, for tilting the bed and for
15 restoring it to its operative position. Such cars are usually provided with locking or supporting devices which hold the car bed in its normal position while transporting the load, and when the dumping mechanism is
20 actuated are automatically released at the appropriate side to permit the load to be dumped, the car bed supporting devices at the opposite side of the car meanwhile remaining in operative position, to prevent
25 the car bed from tilting beyond its normal position when it is being restored to such position. Our present invention has to do more particularly with the devices for holding the car bed in operative position and
30 the mechanism for appropriately actuating them when the car bed is tilted, or restored to its horizontal position, and it consists in the improved construction hereinafter described and pointed out in the claims.

40 In the accompanying drawings:

Figure 1 is a side elevation of part of a car bed embodying our improvements;

Fig. 2 is a cross sectional view showing at one side the power-operated mechanism for
45 rocking the bed, and at the other side the devices for holding the bed in operative position with their connections. In said figure the several parts are shown in the position which they occupy when the car is in its normal or load carrying position. It should be explained in this connection that the parts shown at the left in said figure are located at about the longitudinal center of the car, while the parts shown at the right are lo-

cated near the ends of the car, preferably 55 centrally over the trucks;

Fig. 3 is a view similar to Fig. 2 showing an early stage in the dumping operation;

Fig. 4 is a similar view showing the car bed and the operating mechanism in the 60 position they occupy when the load is being discharged;

Fig. 5 is a view showing in plan the devices by which the sides of the car bed are supported when in operative position; 65

Fig. 6 is a detail, being an enlarged sectional view on line 6—6 of Fig. 2;

Fig. 7 is a view of the parts shown in Fig. 4, showing the car bed tilted in the opposite direction; 70

Fig. 8 is a view showing a modification of some of the parts of the car bed supporting devices; and

Figs. 9—10—11 are views showing another modification. 75

In the drawings we have illustrated our improvements applied to a car of a well-known construction in which the car bed is pivoted along its longitudinal center upon a series of pivots arranged at intervals upon 80 the under body of the car so that it may rock in either direction from its normal position to discharge its load at either side of the car, and it should be understood that the mechanism provided at one side of the 85 car is duplicated at the other side. It will, therefore, suffice to describe only one set of the operating devices.

Referring to the drawings: 9 indicates one of the trucks upon which the under 90 body of the car is mounted, such under body preferably consisting principally of longitudinal I-beams 10—11 spaced apart; near the longitudinal center thereof, and the usual transverse bolsters 13. 14 indicates 95 standards carried by a plate 15 which extends over and is supported by the I-beams 10—11, such standards carrying pivots 16 upon which are mounted hangers 17 secured to the under side of the car bed 18 in any 100 suitable way. These parts may be of any well-known construction, and, if desired, may be arranged so that the car bed may be disconnected from the under body, as is well understood in the art. 19 indicates cushioning stops of the usual type provided at the outer ends of the bolsters 13, as shown in Figs. 2 and 4. The car bed is provided with

the usual side gates 20, arranged to be held up out of operative position in the usual way when the car bed is tilted, to permit the discharge of the load.

- 5 21 indicates one of the compressed air cylinders by the admission to which of compressed air the car bed may be tilted or restored to its operative position. As shown in Fig. 1, these cylinders, of which there are 10 two, one at each side of the car, as above explained, are mounted at the longitudinal center of the car, and are supported by the transverse beams 12. 22 indicates a hollow plunger mounted in the cylinder 21 and arranged to be forced upward by the admission of compressed air to said cylinder. 23 indicates a rocking plunger rod mounted in the plunger 22 and arranged to coöperate with a jointed thrust bar composed of members 24—25 pivoted together at 26 to form a knuckle joint. The upper member 24 is pivoted to one side of the car bed 18 by a pivot 27 so that it swings transversely thereof, and the member 25 is connected by 15 a pivot 28 with a link 29, which, at its inner end, is connected by a pivot 30, shown in dotted lines in Fig. 2, to a depending arm 31 secured centrally to the under side of the car bed 18, as shown in said figure. 32 20 30 indicates a link, one end of which is mounted on the pivot 30, and the other end of which is connected by a pivot 33 to the upper end of the plunger rod 23. The construction and operation of the plunger 22, 35 the plunger rod 23 and the jointed thrust bar are substantially the same as shown and described in the application of Jay B. Rhodes, Serial No. 231,577, filed April 30, 1918, and in Letters Patent to Jay B. Rhodes 40 No. 1,256,163, dated February 12, 1918, and it will, therefore, be sufficient to explain that when the plunger 22 at one side of the car is projected to tilt the bed so as to discharge its load at the opposite side of the 45 car, the upper end of its plunger rod 23 engages the lower end of the member 25, which is then alined with the member 24, and consequently elevates that side of the bed. The thrust bar at the opposite side of the car breaks at the knuckle joint and folds to 50 permit that side of the bed to descend. In restoring the bed to its normal position, the plunger at the dumping side of the car is projected, thereby raising that side of the bed, the plunger at the opposite side having been meanwhile retracted into its cylinder. The parts thus far described separately considered form no part of our present invention.
- 55 60 34 indicates struts, a pair of which are provided near each end of the car at opposite sides thereof. Said struts are pivotally mounted at their lower ends on pivots 35 carried by the bolsters 13, as shown in Fig. 2, and their upper ends are adapted to

underlie blocks 36 which are secured to the under side of the car bed 18 in such position that when the parts are in their several normal positions, the struts 34 bear against the under sides of said blocks, as shown in Fig. 2, and prevent tilting of the car bed in either direction. The engaging surfaces of the struts 34 and blocks 36 are beveled, as shown at 37 in Fig. 2, to facilitate operation of said struts in the manner herein-after described. 38—39 indicate rock-shafts which extend longitudinally of the car over the I-beams 10—11, respectively, as shown in Fig. 2. Adjacent to the cylinders 21 said rock-shafts carry inwardly extending cranks 40 having pins 41, shown in Fig. 5. Said pins are adapted to be engaged by hooks 42 carried by arms 43 which are intermediate pivoted upon the links 32 by pivots 44, as shown in Fig. 2. The hooks 42 are normally held in engagement with the pins 41 by gravity, and the outer ends of the arms 43 normally occupy a substantially horizontal position, as shown in said figure. They are so disposed, however, with reference to the car bed that when the bed is tilted, as shown in Fig. 7, the outer ends of the arms 43 are depressed, thereby moving the hooks 42 up out of engagement with the pins 41, as shown in said figure. Preferably the car bed is provided at its under side with brackets 45 which engage the arms 43 in the manner illustrated. The purpose of this construction will be hereinafter explained.

100 The rock-shafts 38—39 also carry inwardly projecting yokes 46 which are located approximately in the transverse planes in which the struts 34 rock, as shown in Fig. 5, and are provided with downwardly extending lugs 47 which normally bear upon the plate 15, as shown in Figs. 2 and 7. These yokes 46 are provided with pins 48 which extend through longitudinal slots 49 in links 50 which, at their outer ends, are connected by pivots 51 to inwardly projecting lugs 52 carried by the struts 34 near their upper ends, forming toggle connections between the rock shafts 38—39 and the struts 34. Preferably the outer ends of the links 50 are bifurcated as shown at 50^a in Fig. 5. The inner ends of the links 50 extend between the members of the yokes 46, as shown in Fig. 5, and when said links are alined with said yokes they abut against their respective yokes substantially in line with the rock-shafts upon which such yokes are mounted, as shown in Fig. 2. Thus, endwise inward movement of the links 50 is then prevented, and the struts 34 are accordingly held in operative position. When, however, either of the rock-shafts 38 or 39 is rocked, the pin 48 carried by the yoke 46 thereof will swing the inner end of the link 50 connected therewith upward far enough to permit it to move 110 115 120 125 130

- endwise in an inward direction, and consequently permit the struts 34 connected therewith to swing inwardly, as illustrated in Fig. 4. The rocking of one or the other of said 5 rock-shafts 38-39 occurs when the appropriate plunger is projected to tilt the car bed to discharge its load. For example, the parts being in the position shown in Fig. 2, when the plunger rod 23 is projected, its link 10 32 swings upward, and thereby, by reason of the engagement of the hook 42 with the pin 41, rocks the rock shaft 38 in a counter-clockwise direction. The yoke 46 accordingly swings in the same direction, and the 15 pin 48 carries the inner end of the link 50 upward so that it may move endwise into the position shown in Fig. 4. This release of the link 50 occurs before the plunger rod 23 engages the member 25 of the thrust bar, 20 and consequently the strut 34 is released so that it may swing inwardly before the plunger rod 23 begins to tilt the bed. Both struts 34 at the same side of the car are similarly actuated. When the car bed is rocked 25 in the opposite direction to restore it to operative position the rock-shaft at the dumping side is not actuated because, as illustrated at the left in Fig. 7, the hook 42 is then held out of engagement with the pin 41, by the 30 bracket 45 and consequently the projection of the plunger does not affect the rock-shaft, which remains in its normal position and therefore holds the struts 34 at the opposite side of the car in position to arrest the car bed and keep it from going beyond its 35 normal position.
- The struts 34 are positively moved inwardly to permit the bed to be tilted in dumping its load by links 54, which, at their 40 inner ends, are connected by pivots 55 with laterally projecting arms 56 carried by the hangers 31, as shown in Figs. 3 and 7. At their outer ends said links are yieldingly connected with the struts 34 by pivots 57 which pass through slots 58 in the arms of 45 bifurcated heads 59 carried at the outer ends of said links, as shown in Figs. 2 and 6. Thus, a slight amount of lost motion is permitted between the links 54 and the struts 50 34. Between the members of the head 59 a spring 60 is provided which is mounted 55 upon a rod 61 carried by a head 62 mounted on the pivot 57, as shown in Fig. 6, said spring being arranged to normally hold the pivot 57 at the outer ends of the slots 58.
- It will be apparent from the foregoing description that when the car bed is tilted to the right, as shown in Fig. 4, the rocking of the hanger 31 about the axis of the car, which 60 is in line with the pivots 30 and is therefore above the arms 56, will move the links 54 inwardly, thereby swinging the struts 34 in a counter-clockwise direction until finally they assume the position shown in Fig. 4. When 65 the bed is restored to its normal position the swinging of the hangers 31 in the opposite direction positively moves the struts 34 back to their operative position. The purpose of providing the slots 58 is to permit the struts 34 to be moved laterally or inwardly to a 70 limited extent by the yoke 46 and link 50 independently of the links 54 after the struts have been unlocked at the beginning of the dumping operation, as illustrated in Fig. 3, as the links 54 do not come into effective 75 action until after the bed begins to tilt.
- Instead of using the springs 60 at the outer ends of the links 54, a similar result may be secured by employing links 54^a connected with the struts 34 by pivots 57^a and connected with the hangers 31 by rods 61^a which pass through lugs 63 carried by the hangers 31, said rods 61^a having mounted thereon springs 60^a, as shown in Fig. 8. By this construction the links 54^a have a limited endwise movement independently of the hangers 31, and are normally forced outward by the springs 60^a. 80
- By the construction described, it will be noted that the struts 34 are positively moved 90 into their operative or into their inoperative position as required in the operation of the car, and that this operation is controlled automatically by the actuation of the plungers either for tilting the car bed to dump 95 its load, or to restore it to its operative position.
- It is obvious that instead of providing the links 50 with the slots 49 as shown in the principal figures, the same results may 100 be obtained by equivalent means, such as by using yokes 46^a having transverse pins 64-65 spaced apart to receive the links 50^a between them, and providing the links with lugs 66 adapted to engage the pins 64, as 105 illustrated in Figs. 9-10-11. This is substantially a transposition of the construction shown in the earlier figures, as the pins 64-65 between the yoke members in co-operation with the lug 66 are the equivalent 110 of the slot 49 and pin 48.
- What we claim as our invention and desire to secure by Letters Patent, is—
1. A dump car comprising a suitable under body, a car bed mounted to rock thereon, power operated mechanism for tilting the bed, laterally swinging integral struts between the under body and the sides of the bed for normally holding the bed in its normal position, members connected respectively with the under body and with said struts and co-operating to hold said struts in operative position and operated by the actuation of said power operated mechanism to dump the bed to release the struts at the 125 dumping side of the car, and means for positively moving said struts into operative position when the car bed is righted.
  2. A dump car comprising a suitable under body, a car bed mounted to rock there- 130

on, power operated mechanism for tilting the bed, laterally swinging struts between the under body and the sides of the bed for normally holding the bed in its normal position, means for holding said struts in operative position and operated by the actuation of said power operated mechanism to dump the bed to release the struts at the dumping side of the car, and means connected with the car bed below the axis thereof and with said struts for moving said struts into operative position when the car bed is righted.

3. A dump car comprising a suitable under body, a car bed mounted to rock thereon, power operated mechanism for tilting the bed, laterally swinging struts between the under body and the sides of the bed for normally holding the bed in its normal position, rock-shafts actuated by said power operated mechanism, toggle connections between said rock-shafts and said struts and operated by the actuation of said power operated mechanism to dump the bed to release the struts at the dumping side of the car, and means for positively moving said struts into operative position when the car bed is righted.

4. A dump car comprising a suitable under body, a car bed mounted to rock thereon, power operated mechanism for tilting the bed, laterally swinging struts between the under body and the sides of the bed for normally holding the bed in its normal position, rock-shafts actuated by said power operated mechanism, toggle connections between said rock-shafts and said struts and operated by the actuation of said power operated mechanism to dump the bed to release the struts at the dumping side of the car, and means connected with the car bed and with said struts for moving said struts into operative position when the car bed is righted.

5. A dump car comprising a suitable under body, a car bed mounted to rock thereon, power operated mechanism for tilting the bed, laterally swinging struts between the under body and the sides of the bed for normally holding the bed in its normal position, means for holding said struts in operative position and operated by the actuation of said power operated mechanism to dump the bed to release the struts at the dumping side of the car, and links connected with the car bed and with said struts for moving said struts into operative position when the car bed is righted.

6. A dump car comprising a suitable under body, a car bed mounted to rock thereon, power operated mechanism for tilting the bed, laterally swinging struts between the under body and the sides of the bed for normally holding the bed in its normal position, rock-shafts actuated by said power operated mechanism, toggle connections be-

tween said rock-shafts and said struts and operated by the actuation of said power operated mechanism to dump the bed to release the struts at the dumping side of the car, and links connected with the car bed and with said struts for moving said struts into operative position when the car bed is righted.

7. A dump car comprising a suitable under body, a car bed mounted to rock thereon, power operated mechanism for tilting the bed, laterally swinging struts between the under body and the sides of the bed for normally holding the bed in its normal position, means for holding said struts in operative position and operated by the actuation of said power operated mechanism to dump the bed to release the struts at the dumping side of the car, and links connected with the car bed below the axis thereof and with said struts for moving said struts into operative position when the car bed is righted.

8. A dump car comprising a suitable under body, a car bed mounted to rock thereon, power operated mechanism for tilting the bed, laterally swinging struts between the under body and the sides of the bed for normally holding the bed in its normal position, means for holding said struts in operative position and operated by the actuation of said power operated mechanism to dump the bed to release the struts at the dumping side of the car, and links connected with the car bed below the axis thereof and with said struts for moving said struts into operative position when the car bed is righted, the connections between said struts and the car bed being arranged to permit limited inward movement of said struts independently of movement of the bed.

9. A dump car comprising a suitable under body, a car bed mounted to rock thereon, power operated mechanism for tilting the bed, laterally swinging struts between the under body and the sides of the bed for normally holding the bed in its normal position, rock-shafts actuated by said power operated mechanism, yokes carried by said rock-shafts, links connected with said struts and having a slotted connection with said yokes, and means for moving said struts into operative position when the car bed is righted.

10. A dump car comprising a suitable under body, a car bed mounted to rock thereon, power operated mechanism for tilting the bed, laterally swinging struts between the under body and the sides of the bed for normally holding the bed in its normal position, rock-shafts actuated by said power operated mechanism, yokes carried by said rock-shafts, links connected with said struts and having a slotted connection with said yokes, said links connected with the car bed below the axis thereof and with said struts

for moving said struts into operative position when the car bed is righted.

11. A dump car comprising a suitable under body, a car bed mounted to rock thereon, 5 power operated mechanism for tilting the bed, laterally swinging integral struts between the under body and the sides of the bed for normally holding the bed in its normal position, and members connected respectively with the under body and with said 10 struts and coöperating to hold said struts in operative position, and operated by the actuation of said power operated mechanism to dump the bed to release the struts at the 15 dumping side of the car.

12. A dump car comprising a suitable under body, a car bed mounted to rock thereon, power operated mechanism for tilting the bed, laterally swinging struts between the under body and the sides of the bed for normally holding the bed in its normal position, 20 rock-shafts actuated by said power operated mechanism, and toggle connections between said rock-shafts and said struts and operated by the actuation of said power operated mechanism to dump the bed to release the struts at the dumping side of the car. 25
